UNITED STATES PATENT OFFICE.

DAVID L. ROSCOE, OF THE UNITED STATES ARMY, ASSIGNOR OF ONE-FOURTH TO JOHN PITCHER, OF THE UNITED STATES ARMY, AND ONE-FOURTH TO CHARLES A. MASON, OF WASHINGTON, DISTRICT OF COLUMBIA.

COUNTING DEVICE.

No. 909,823.

Specification of Letters Patent. Patented Jan. 12, 1909.

Application filed October 8, 1908. Serial No. 456,709.

To all whom it may concern:

Be it known that I, DAVID L. ROSCOE, 2nd lieutenant United States Army, citizen of the United States, have invented certain 5 new and useful Improvements in Counting Devices, of which the following is a specification.

This invention relates to counting devices, and particularly to counting devices for 10 games.

The invention will be described and illustrated as embodied in a scoring or counting board for use in the game of bridge whist, and while this is the preferred embodiment 15 of the invention it is to be understood that many features of the invention will be found useful in counting devices generally.

The usual, and perhaps the most popular method of keeping a record or score of the 20 various items necessary to be counted during the progress of the game of bridge whist is to mark down on a score card, or other paper, the number of points and honors to be credited to either side in two columns under the 25 words "We" and "They", the former of these words referring to the side of the score-keeper, and the latter to that of his or her opponents. The numbers of the honors and points in the two columns are subsequently added to get the total number of 30 points for each side. Separate notations are also usually made on the card to indicate the number of games and rubbers won by each side. This method of keeping score is 35 objectionable as being laborious and inconvenient, as it frequently calls for a lengthy and tedious calculation at the end of a series of games to add the long columns of figures denoting the points, honors, etc. Another 40 objection applying to this method of scoring is that the pencil and paper used to keep the score often are misplaced or lost, causing vexatious delays.

Under one form of this invention an object is to provide, in a very compact and convenient form, a device so constructed as to be attached to the under side of a table, or to

lie upon the upper surface thereof, and having an improved arrangement of counters which will permit any number of items in a 50 game, as for instance in bridge whist, to be recorded, or scored, during the progress of the game, and which will, furthermore, permit such items to be subsequently added to obtain the total points scored, with a minimum amount of labor, and in a very simple 55 and effective manner.

This device in its preferred form comprises a frame divided into a suitable number of sections providing spaces each of 60 which contains a plurality of rods or guides of special form, arranged in parallel relation. Each of these guides carries a series of counters, which have apertures agreeing with the cross-sections of the guides, whereby the counters are freely slideable on the 65 guides, and are prevented from turning thereon. The counters may be in the form of blocks, of rectangular or other suitable configuration, and such counters have, preferably, slightly beveled edges upon which are placed suitable numerals, arranged in the manner and for the purpose to be herein-after more fully described. As herein shown, the various sections of the frame are arranged to represent the several items necessary to be counted in the game of bridge whist, as, "Honors," "Points," "Totals," "Games," and "Rubbers," and a set of 70 counters, for each of said items, is provided 80 in duplicate for the two sides playing the game. The frame is also preferably provided, at a suitable point, with printed information as to the value of the tricks in the various suits, the value of honors in the various suits, etc. 85

Referring to the drawings: Figure 1 represents a plan view of the invention complete. Fig. 2 is a cross-sectional view on the line 2—2 Fig. 1, and Fig. 3 is a detail view, 90 showing, in perspective, some of the counters, and their guide.

Similar reference characters denote similar parts throughout.

The frame A is constructed conveniently of elongated, rectangular form, or it may be of any other form desired. As shown, this frame is divided centrally by a strip B into 5 two equal parts or sections, each of which is in turn divided into three sections by the strips C, to provide spaces, as shown. The several sections on each side of the dividing strip B contain counters for keeping score, 10 those on one side, marked "We," being for the scorer and his or her partner, and those on the opposite side, marked "They," being for their opponents, as will be apparent. As the sections on one side of the strip B are 15 duplicates of those on the opposite side thereof, a description of one set of such sections and their counters will be sufficient to enable the entire device to be understood.

The guides D, which are preferably in 20 the form of flattened strips, are arranged in spaced, parallel relation, and extend longitudinally of the spaces provided by the sections, the ends of the guides being rigidly secured to the walls bounding such spaces.

25 The counters E are, as herein shown, in the form of blocks and have their upper edges beveled in order to present the numerals, which are placed upon such edges, at the proper angle to the eye when the frame occupies a position slightly distant from the score keeper. This construction, I have found, enables the numerals to be quickly and readily distinguished, and is a feature 30 of importance in this invention. The counters are slotted or otherwise suitably apertured to conform to the flattened cross-section of the guides D upon which the counters freely slide, by which construction the counters are restrained against rotation on their guides, and are, moreover, not so easily displaced by the jarring of the table upon which the frame may rest, or to which it may be attached, or by shaking the frame 35 when the same is moved.

40 Each of the several sections of the frame, designated as "Honors," "Points" and "Totals," respectively, contains, preferably, four guide rods, D, and each of said rods carries a series of counters, as ten, numbered 1, 2, 3, 4, 5, 6, 7, 8, 9, 0, in regular order, beginning at 45 the top of the section. In another part of the frame, as, for instance, above the spaces containing the counters denoting honors, points and totals, are located, in duplicate, the guides D¹ upon which are slidably mounted two counters D², to indicate the games won by each side in a rubber, these counters, respectively, bearing the appropriate numerals, as 1, 2. Arranged in close relation to these guides and their counters are the guides D³ carrying the counters D⁴, the same serving to indicate, in like manner, the rubbers won, and bearing the appropriate numerals therefor, as 1, 2, 3, 4, 5, 6, 7, 8, 9, 0.

Preferably, the guide rods carrying the counters for indicating the number of games and rubbers won are arranged to extend transversely to the longest dimension of the frame, and to the direction of the 70 guides, D. Below the sections occupied by the counters which denote the totals I may, and preferably do, provide the frame with a marginal space G upon which will be written or printed in any suitable manner, and 75 in convenient form, the necessary information as to the value of the tricks, honors, etc., in the various suits, in bridge whist.

If desired, the frame A may be provided 80 with an attaching ear or tab F having an aperture to receive a screw or nail, whereby to secure the frame to the underside of a table in such manner as to permit it to swing 85 out of the way, or into position for use, as desired.

From the above description it is believed 90 that the nature of the device and mode of operation will be readily understood. Reading from right to left, the counters in the several rows under "Honors," "Points" and "Totals," represent units, tens, hundreds and thousands, and the honors and points are counted by sliding up the counters containing the appropriate numerals to 95 indicate the number of these items to be credited to each side as they are won, during the progress of the game. As the rows of counters representing units, tens, hundreds and thousands under "Honors" are 100 in the same line, respectively, with the rows of counters representing units, tens, hundreds and thousands under "Points" and "Totals," it will be seen that the honors and points may be added and the totals obtained 105 in a very simple manner. In scoring, the counters indicating the honors, points, and totals, are moved on the guides from their lowest to their highest positions thereon, and the counters indicating games and rubbers, are moved from left to right, or from 110 right to left. Suppose, for example, the scorer's opponents should make twenty-eight points. Two counters on the second guide from the right-hand side of the frame, and eight counters on the first guide from said side, will be raised from their positions shown in the drawing, to the upper part of the space under "Points," the numerals upon the lowermost of the shifted counters will 115 then read 28. If additional points are to be entered up, they may be added to this score, and if the added points reach one hundred, or more, the proper counter on the third guide rod will be shifted, and so on. The 120 same method may be practiced in scoring honors, and, when the totals are desired, but a moment is required to add the units, tens, hundreds and thousands scored in the 125 aligned columns of "Honors" and "Points," 130

and to shift the appropriate counters on the guides in the "Totals" space to indicate the sum of such honors and points.

The manner of counting the games and rubbers will be apparent without further description.

Having thus described my invention, what I claim as new and desire to secure by Letters Patent of the United States is:

10 1. A counting device comprising a frame divided into sections, each of said sections containing a plurality of groups of independent, bodily movable members, consecutively numbered from unity in each group, 15 the groups representing, respectively, units, tens, hundreds, etc., said members in groups of the same denomination being in alinement, whereby to facilitate the addition of the numerals in the several groups and 20 means for retaining the members of each group in serial order.

2. A counting device comprising a number of sections each having a plurality of groups of independent, bodily movable members, 25 each group representing a denomination, the members of each group being consecutively numbered from unity, and means for confining the members of each group to movements in a line parallel with the movements of the 30 members in the adjacent groups, and for holding the members of each denomination in alinement.

3. A counting device comprising a plurality of groups of independent, bodily movable members, the members of each group being consecutively numbered from unity and said groups being adapted to represent, respectively, different denominations, and means 40 for restricting the members of each group to movements in a definite path whereby said members are retained in serial order.

4. A device of the class described comprising a frame, a series of guides thereon arranged side by side, each of said guides carrying a plurality of movable counters consecutively numbered to indicate the score under an item of a game, a second series of guides in line with the first series and each carrying a plurality of counters consecutively numbered to indicate the score under 50 another item of a game, and means to totalize the numbers scored by the said counters.

5. A device of the class described comprising a frame, a series of guides thereon arranged side by side, each of said guides carrying a plurality of movable counters consecutively numbered to indicate the number scored under an item of a game, a second series of guides arranged in line with the first series and each carrying a plurality of movable counters consecutively numbered to indicate the number scored under another item of a game, and a third series of guides arranged in line with those of the second se-

ries and each carrying a plurality of movable counters to indicate the sum of the numbers scored by the two first-mentioned series of counters.

6. A scoring device for bridge whist comprising a frame carrying a set of movable counters to indicate the number of honors; a set of movable counters to indicate the number of points; and a set of movable counters to indicate the sum of the honors and points as scored by their respective counters the counters in the several sets being consecutively numbered and arranged in independent rows to denote, respectively, units, tens, hundreds and thousands, and the counters in rows of the same denomination being in alinement.

7. A scoring device for two sides in bridge whist comprising a frame constructed with a section containing a plurality of rows of movable counters, to indicate honors; a section containing a plurality of rows of movable counters to indicate points; and a section containing a plurality of rows of movable counters to indicate totals, the counters being consecutively numbered in each row and the rows in each series being in alinement with the rows of the adjacent series.

8. A scoring device for two sides in bridge whist comprising a frame divided longitudinally into two sections each of which is in turn divided transversely into three sections; independent sets of movable counters located in the several sections and arranged to indicate, respectively, the honors, points and totals for the two sides; and duplicate sets of movable counters to indicate, respectively, the games and rubbers won, the last-named sets of counters being arranged to move transversely to the direction of movement of the first named sets of counters.

9. A scoring device for bridge whist comprising a frame divided longitudinally into two sections each of which is in turn divided transversely into three sections; independent sets of movable counters serially numbered from unity and located in the several sections, and arranged to indicate, respectively, the honors, points and totals for the two sides.

10. In a game scoring device, a frame having a guide thereon, in combination with counters having apertures to fit said guide whereby to slide thereon, said counters having beveled edges provided with numerals.

11. In a game scoring device, a frame having a guide thereon, in combination with counters having apertures to fit said guide, and constructed to slide but restrained against rotation thereon, said counters having beveled edges provided with numerals.

12. A scoring device for bridge whist comprising a frame carrying flattened guides; independent sets of consecutively numbered

blocks having apertures to fit said guides and slide thereon, to denote the honors; other flattened guides, and independent sets of counters consecutively numbered from unity and having apertures to fit said guides and slide thereon to denote the points; and other flattened guides, and independent sets of counters consecutively numbered from unity and having apertures to fit said guides and

slide thereon to denote the totals, the members of the several sets of guides being in alinement.

In testimony whereof I have affixed my signature in presence of two witnesses.
